(57) **CLAIM**

The ornamental design for a notebook computer, as shown and described.

DESCRIPTION

FIG. 1 is a front perspective view of a notebook computer showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof; and,
FIG. 7 is a bottom view thereof;
FIG. 8 is a rear perspective view of the notebook computer in which the notebook computer is shown in an open position; and,
FIG. 9 is a left-side view thereof.
The broken lines are for environmental purposes only and form no part of the claimed design.
